AIR PURIFIER

George Bernhardt Gelakoski, Aurora, Ill.

Application October 4, 1937, Serial No. 167,304

2 Claims. (CL. 261—88)

This invention relates to a device for cleaning air with water and chemicals, producing such results as purifying, sterilizing, deodorizing, humidifying, cooling or heating breathing air.

5 An important object of the invention is to provide a device of this character having means to draw the air to be treated into the body portion of the device, where the air is treated and exhausted from the device in a purified or chemically treated condition.

10 Another object of the invention is to provide means for drawing liquid contained in a tank at the base of the body portion of the device where it is broken into a fine spray, the air passing 15 through the device also passing through the fine spray where it is treated in a manner as described.

15 A still further object of the invention is to provide a device of this character wherein the operation thereof may be reversed so that the device may be positioned adjacent to the ceiling of a mine to treat the gas which usually collects at the ceiling of the mine.

20 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

25 Referring to the drawings:

30 Figure 1 is a vertical sectional view through a device constructed in accordance with the invention.

Figure 2 is a transverse sectional view taken on line 2—2 of Figure 1.

35 Figure 3 is a transverse sectional view taken on line 3—3 of Figure 1.

Figure 4 is a sectional view taken on line 4—4 of Figure 1.

40 Figure 5 is an enlarged fragmental detail sectional view illustrating the connection between the vertical water tube and the fan blades.

Figure 6 is an elevational view of the apparatus housed in a cabinet, a portion of the cabinet being broken away illustrating the cooling coils mounted therein.

45 Figure 7 illustrates a modified form of pump.

50 Referring to the drawings in detail, the device includes a body portion indicated generally by the reference character 5, which body is preferably cylindrical in formation and provided with

the base 7, on which the body portion is supported. Positioned within the body portion 5 is the tank 6 adapted to contain water for the treatment of the air passed through the body portion.

55 Supported on the top of the body portion, is a motor 13, which motor operates the shaft 14 that extends through an opening in the top of the body portion, the lower end of the shaft 14 being threaded to be fitted into a threaded opening of the bearing 15, which is hollow so that water may pass therethrough. The reference character 16 designates fan blades which extend laterally from the bearing 15, and as shown these fan blades are hollow and provided with openings 17 through which the water may pass, and since the blades 16 are rotated rapidly, it is obvious that the water will be broken into a fine spray.

60 Resting in the tank 6, is a water tube 18 which has a flared upper extremity 19 that fits within the bearing 15, under normal conditions. At the base of the tube 18 are openings 20 through which water may pass from the tank 6, into the tube 18.

65 A rod 21 is supported by the shaft 14, and has threaded connection with the shaft 14 at 22, the lower end of the rod being supplied with a worm 23 of a diameter to closely fit within the tube 18 to lift the water contained in the tube 20 and cause the water to pass upwardly through the tube and into the blades, where it is thrown in a manner as previously described.

70 In connection with the water lift, it might be stated that the rotary bladed pump 9 may be used in lieu of the worm 23, if preferred.

75 As clearly shown by Figure 1 of the drawings, the body portion is provided with lower lateral openings 24 and upper lateral openings 25, which openings establish communication between the interior of the body portion and the vertical pipes 26, there being provided partitions 27 and 28 in the pipes 26 for dividing the upper portions of the pipes from the lower portions thereof.

80 Openings 29 are formed in the pipes 26 and are located at points slightly above the openings 24, the openings 29 constituting the inlet openings to allow air to pass into the body portion of the device. Disposed directly above the fan blades 16, are openings 31 through which air passes from the lower chamber to the upper chamber, there being provided blades 30 operated by the rod 28 to control the size of the openings 31, whereby the volume of air passing from the

lower compartment to the upper compartment may be regulated to meet various conditions.

Heating elements 32 are provided in the pipes 26 and are in circuit with a suitable source of electric supply through the wires 33 and 34, the wires 33 and 34 being supplied with a plug 35 which may be positioned in the usual wall socket of a room.

Supported within one of the pipes 26, is an open, electrically heated container 41, adapted to contain chemicals which when heated will throw-off vapors to treat the air.

As illustrated by Figure 7 of the drawings, the apparatus is supported within the cabinet indicated by the reference character 42, the section 43 of the cabinet housing the coils 44 which are cooled by the electric refrigerating apparatus 45, of well known construction. The cooler and evaporator 46 are also supported within the section 43.

Extending through the section 43, is a pipe 47 leading from the blower 48, whereby air may be forced into the lower end of the body portion 5, to be carried through the body portion as described.

Openings 49 and 50 establish communication between the main body portion 5 and section 43 of the cabinet whereby air treated in the body portion may pass into the section 43 and over the coils 44, exhausting into the room through the screened opening 51 formed in the top of the section 43.

It might be further stated that the pipes 26 have their discharge ends disposed adjacent to the openings 51 in top of the cabinet, the openings being covered by the wire mesh material 53. Closures 54 are mounted on the cabinet and control the passage of treated air from the apparatus.

When the apparatus is used for purifying air in mines, it is pointed out that the device is supported adjacent to the ceiling of the mine so that the gas and foul air collecting adjacent to the ceiling of the mine may be treated.

If the device is to be used as a humidifier, liquid is placed in the tank 6, the motor is set in operation and the liquid is carried upwardly through the tube 18 and forced laterally into the blades 16 which blades are rotated with the result that the liquid will be thrown through openings of the blades to mingle with air passing through the body portion of the device and which is drawn through the device by the fan blades 16.

After the air has been treated, it is passed up-

wardly through the pipe 26 and discharged at the open ends thereof.

The reference character 60 designates the feed pipe through which the water flows to the tank 6, there being provided a float actuated valve 61 on the discharge end of the pipe for controlling the flow of water through the pipe. An overflow pipe 62 also extends into the tank 6 and carries off any excess quantity of water, which may enter the tank.

It will of course be understood that the device may be used as a humidifier, deodorizer, disinfecting device or for any other similar purpose, by merely changing the liquid held in the tank 6.

I claim:

1. In an air conditioning device, a body portion, the lower end of said body serving as a tank for a liquid, a partition above the body portion and dividing the tank into upper and lower air compartments, said partition having openings, means for regulating the sizes of the openings varying the quantity of air passing upwardly into the upper air compartment, said body portion having lateral openings above and below the partition, vertically extending pipes connected with the body portion at the openings, curved partitions within the pipes and arranged adjacent to and laterally of the first mentioned partition, said pipes having an air inlet opening below the partitions thereof, means for drawing air into the portion of said pipe beneath the last named partition through said openings below said first named partition and through said body portion and means for spraying water from the tank into the air as the air passes through the body portion.

2. In an air conditioning device, a body portion, the lower end of said body serving as a tank for liquid, a partition dividing the body portion into upper and lower air compartments, said partition having openings, means for regulating the sizes of the openings to vary the quantity of air passing into the air compartment, vertically extending pipes connected with the body portion above and below the partition, said pipes having air inlet openings, a fan within the body portion for drawing air into the body portion and forcing air into the air compartment, said fan including hollow blades, a hollow shaft on which the fan is mounted, means in the hollow shaft for directing water into the blades and upper end of the body portion where the water is sprayed into the incoming air, and means for controlling the passage of air through the pipes.

GEORGE BERNHARDT GELAKOSKI. 55
